UNITED STATES PATENT OFFICE.

D. M. WESTON, OF BOSTON, MASSACHUSETTS.

IMPROVEMENT IN RECIPROCATING PUMPS.

Specification forming part of Letters Patent No. **56,129**, dated July 3, 1866.

To all whom it may concern:

Be it known that I, DAVID M. WESTON, of Boston, in the county of Suffolk and Commonwealth of Massachusetts, have invented a new and useful Improvement in Reciprocating Pumps; and I do hereby declare that the following is a full and exact description thereof, reference being had to the accompanying drawings, and to the letters of reference marked thereon.

To enable others skilled in the art to make and use my invention, I will proceed to describe its construction and operation.

In reciprocating pumps as at present constructed, with each stroke of the piston the piston-head strikes the water or other fluid to be pumped with a sensible jar or concussion, commonly called "the water-hammer," which increases with the speed of the pump actions, so that a rapid action of the pump is destructive to the machinery.

In my invention I overcome this difficulty by attaching springs, made of cylindrical rings of rubber or other elastic material, to the end of the piston-rod, and as part of the connection between the piston-rod and the driving-gear.

Upon the accompanying drawings, Figure 1 is a plan of the upper surface of the cross-head. Fig. 2 is a plan of the lower surface of

the cross-head. Fig. 3 is a front elevation of my invention. Fig. 4 is a section of the same.

Upon the connecting-rod P, I place the metal flanges A A, the lower flanges resting upon a shoulder in the connecting-rod P, the upper confined and adjusted in its position by two nuts, the upper of which is a binding-nut. Between these flanges are placed rubber rings C C, one above and one below the cross-head B. The cross-head is made to fit loosely upon the piston-rod P, between the two cushions or springs C C, which, being of an elastic material, relieve the driving-gear from any jar or concussion in the action of the pump.

I do not confine myself to rubber springs or cushions, for other elastic material may be used, nor to any particular location between the driving machinery and the pump-piston.

I claim—

The cushions or springs C C, made of rubber or other elastic material, or their equivalents, so placed as to form part of the connection between the piston of a pump and the driving-gear, substantially as above described, for the purpose of relieving the pump and machinery from jar or concussion.

D. M. WESTON.
